UNITED STATES PATENT OFFICE.

WILLIAM H. BETTS, OF ST. LOUIS, MISSOURI, ASSIGNOR TO BETTS SOLE PROTECTOR COMPANY, OF ST. LOUIS, MISSOURI, A CORPORATION OF MISSOURI.

DESIGN FOR A SOLE-PROTECTOR.

54,718.

Specification for Design.

Patented Mar. 23, 1920.

Application filed July 11, 1919. Serial No. 310,279. Term of patent 14 years.

To all whom it may concern:

Be it known that I, WILLIAM H. BETTS, a citizen of the United States, residing at St. Louis, Missouri, have invented a new, original, and ornamental Design for Sole-Protectors, of which the following is a specification, reference being had to the accompanying drawing, forming part thereof, in which—

Figure 1 is an enlarged top plan view of a sole protector embodying my invention; Fig. 2 is the side elevation of the same; Fig. 3 is an end elevation.

The leading feature of my design consists of the employment of a substantially elliptical body portion 4 which is provided with a series of substantially V shaped grooves 5, thus dividing the substantially elliptical body shaped portion 4 into a series of diamond shaped portions or bodies 6.

Another leading feature of my design is to provide the body portion of 4 with integral tapered and curved projections 7. These projections gradually tapering and curving from the head 4 to their points. These projections are rectangular in end elevation as illustrated in Fig. 3.

I claim:

The ornamental design for a sole protector as shown and described.

In testimony whereof, I have signed my name to this specification, in presence of two subscribing witnesses.

WILLIAM H. BETTS.

Witnesses:

WALTER C. STEIN,
EDWARD E. LANGAN.
